UNITED STATES PATENT OFFICE.

GEORGE F. McINDOE, OF EVERETT, MASSACHUSETTS.

REVOLVING CALENDAR.

SPECIFICATION forming part of Letters Patent No. 244,469, dated July 19, 1881.

Application filed February 14, 1881. (No model.)

To all whom it may concern:

Be it known that I, GEORGE FRANCIS McINDOE, of Everett, Massachusetts, have invented a new and useful Form for a Calendar, 5 of which the following is a specification.

My invention relates to a new and original form of revolving calendar, the circle of figures indicating the days of the month being stationary, the letters indicating days of the 10 weeks and months revolving from a common center, that they may be made to register any day or month. I attain this effect by the mechanism illustrated in the accompanying drawings—similar letters refer to similar parts—in 15 which—

Figure 1 is the vertical face complete. Fig. 2 represents the central disk, in shape substantially as illustrated, with figures representing the days of the month around the margin, and provided with an opening, through 20 which is seen the name of the month, and the apron *b*, which is perforated at *d*, cut in the same disk, for the purpose of covering a part of disk *B*. Fig. 3 represents a disk with names 25 of months upon the margin and provided with perforations *e*. Fig. 4 represents a disk divided into thirty-seven equal parts for inserting letters to denote days of the weeks, and has seven perforations, *f*; Fig. 5 a sectional 30 view of Fig. 1. Fig. 6 represents the pin *g*

attached to the spring *D*, which spring is held in position by the eyelet *c*. The eyelet also holds the disks together. The pin is used to prevent the accidental moving of disks when set for any month.

35

To set the calendar for any given month, remove the pin *g* from perforations by means of spring *D*; revolve disk *C* till name of month shows through opening *a*; then revolve disk *B* till the day of the week on which the month 40 begins comes under figure 1 on margin of disk *A*, which will bring a perforation in each disk under the pin, into which the pin will move when the spring is released.

What I claim as my invention, and desire 45 to secure by Letters Patent, is—

A revolving calendar composed of the back disk, *C*, having the month-names in marginal series, the middle disk, *A*, having marginal day-numerals, slot *a* for showing month-names, 50 and apron *b*, and the front disk, *B*, of less diameter than the others, overlapped by the apron *b* and bearing thirty-seven marginal day-initials, said disks moving on a central pivot and co-operating substantially as and 55 for the purpose described.

GEORGE FRANCIS McINDOE.
